[57] CLAIM

The ornamental design for a systems controller for an air mattress, as shown and described.

DESCRIPTION

FIG. 1 is a perspective view of the front and right side of a systems controller for an air mattress showing my new design;

FIG. 2 is a front view of the systems controller for an air mattress of FIG. 1;

FIG. 3 is a left side view of the systems controller for an air mattress of FIG. 2;

FIG. 4 is a right side view of the systems controller for an air mattress of FIG. 2;

FIG. 5 is a bottom view of the systems controller for an air mattress of FIG. 2;

FIG. 6 is a top view of the systems controller for an air mattress of FIG. 2 thereof;

FIG. 7 is a rear view of the systems controller for an air mattress of FIG. 2; and,

FIG. 8 is a rear view similar to FIG. 7 with optional cutouts and screw holes deleted from the rear surfaces.

The broken line showing of a rotary dial and on/off switch, in FIG. 1, is for illustrative purposes only and forms no part of the claimed design.
